UNITED STATES PATENT OFFICE

156,471

FLOWER DISPLAY STAND OR THE LIKE

Frank U. Winchester, Lansing, Mich.

Application August 6, 1948, Serial No. 147,967

Term of patent 7 years

(Cl. D35—3)

To all whom it may concern:

Be it known that I, Frank U. Winchester, a citizen of the United States, residing at Lansing, in the county of Ingham and State of Michigan, have invented a new, original, and ornamental design for a Flower Display Stand or the like, of which the following is a specification, reference being made to the accompanying drawing, forming part thereof.

The figure is a perspective view of a flower display stand or the like, showing my new design.

I claim:

The ornamental design for a flower display stand or the like, substantially as shown.

FRANK U. WINCHESTER.
